UNITED STATES PATENT OFFICE.

EDWARD ALEXANDER, OF PROVIDENCE, RHODE ISLAND.

DESIGN FOR A NAME-PLATE FOR BICYCLES.

SPECIFICATION forming part of Design No. 25,919, dated August 11, 1896.

Application filed July 6, 1896. Serial No. 598,238. Term of patent 31 years.

To all whom it may concern:

Be it known that I, EDWARD ALEXANDER, of Providence, in the county of Providence and State of Rhode Island, have invented and produced a new and original Design for Name-Plates for Bicycles; and I do hereby declare that the following is a full, clear, and exact description thereof, reference being had to the accompanying drawing, which forms a part thereof.

The drawing represents an elevation of the plate, showing the design.

The leading features of my design consist of a shield with the stars and stripes of the arms of the United States thereon standing in front of two United States flags, one of which is inclined to the right and one to the left, the whole being surmounted by an eagle

perched on the shield and having his wings extended along the flagstaffs, one to the right and one to the left. Below the drapery of the flags at the bottom a folded scroll is placed across in a downwardly-curved line and a pendant composed of two shell-like scrolls, one turned to the right and the other to the left, with a downwardly-projecting point placed between them.

What I claim is—

The design for a name-plate for bicycles, substantially as herein shown and described.

In testimony whereof I have hereunto set my hand.

EDWARD ALEXANDER.

In presence of—

BENJ. ARNOLD,

JAMES E. ARNOLD.
